UNITED STATES PATENT OFFICE

2,655,234

BRAKE BEAM WITH FIXED HEAD AND GUIDE

Walter H. Baselt, Chicago, Ill., assignor to American Steel Foundries, Chicago, Ill., a corporation of New Jersey

Application September 22, 1945, Serial No. 617,966

22 Claims. (Cl. 188—223.1)

1

This invention relates to brake beams and more particularly to a novel fabricated truss type brake beam adapted for utilization in the brake rigging of a railway car truck.

A general object of the invention is to provide a novel fabricated beam of the above-described type wherein all of the parts are welded together to form a relatively light structure capable of resisting the loads to which such a beam is subjected under railway service conditions.

A more specific object of the invention is to design a brake beam structure such as above described wherein each brake head is provided with a box-section portion housing the adjacent ends of the tension and compression members of the truss structure, said structure being welded to the brake head.

Another object of the invention is to design a beam such as above described wherein the box-section portion of the brake head is provided with guide means for the tension member of the beam, thereby affording an exceptionally rigid structure.

In one embodiment of the invention the novel brake beam is of the so-called "Unit" type wherein the ends of the beam are provided with relatively narrow guide portions adapted for reception within brackets formed on the associated truck frame, and in other illustrated embodiments of the invention, the novel beam is of more standard design wherein the brake heads are provided with hanger sockets adapted for connection to associated hangers swingably supported by the truck frame in conventional manner.

The foregoing and other objects and advantages of the invention will become apparent from a consideration of the following specification and accompanying drawings wherein:

Figure 1 is a fragmentary top plan view of a brake beam embodying the invention;

Figure 2 is an end elevation of the structure shown in Figure 1;

Figures 3 and 4 are sectional views taken respectively in the vertical planes indicated by the lines 3—3 and 4—4 of Figure 1;

Figures 5—8 illustrate a modification of the invention, Figure 5 being a fragmentary top plan view of the beam, Figure 6 being an end view of the structure shown in Figure 5, Figure 7 being a fragmentary rear elevation of the structure shown in Figure 5, and Figure 8 being a sectional view taken in the vertical plane indicated by the line 8—8 of Figure 5;

Figures 9 and 10 illustrate another modification

of the invention, Figure 9 being a fragmentary top plan view of the beam, and Figure 10 being a side elevation of the structure shown in Figure 9.

5 Describing the invention in detail and referring first to the preferred embodiment thereof illustrated in Figures 1—4 inclusive, the brake beam comprises a truss structure including a channel or U-section compression member 2, a tension member 4, and a fulcrum 6 connected therebetween, said fulcrum being slotted as at 8 to accommodate an associated brake lever (not shown). Each end of the beam is provided with a brake head 10 comprising a box-section truss lock portion including top and bottom walls 12 and 14, a front wall 16, and a rear wall 18 slotted as at 20 for the purpose hereinafter described. The outer or outboard end of the box-section portion of the brake head is offset to afford a relatively narrow guide portion or boss 22 projecting outboardly from an outboard brake head wall 23 and adapted for reception within a guide bracket of an associated truck frame (not shown).

15 The top and bottom walls 12 and 14 are connected at the outer extremity thereof by an end wall 24 cored away as at 26 for convenient foundry practice. It may be noted that the end wall 24 is provided adjacent the rear extremity thereof with an inwardly extending lug 27 between the offset portions of the top and bottom walls 12 and 14 and defining a socket therewith receiving the outboard end of the tension member 4. The lug 27 presents a diagonal guide surface 29 engaging the diagonal tension member 4 at the outer extremity thereof. The lug 27 also functions to dam weld metal within the before-mentioned slot 20 during a welding process in which the brake head and associated truss structure are fused together to form an integral structure, as hereinafter described.

20 25 30 35 40 45 50 The inner extremities of the top and bottom walls 12 and 14 are connected by an inner end wall 28 with a slot or socket 30 receiving the tension member 4 to afford convenient guide means therefor. A bifurcated filler block, generally designated 32, is fitted within the compression member 2 in abutment with the rear web thereof and comprises spaced legs 34, 34 (Figure 4) snugly embracing the tension member 4. The block affords rigidity to the structure and provides back-up metal for a weld within the slot 20, said weld being effective to fuse the members 2, 4, 18 and 32 into an integral structure, the fused area being diagrammatically indicated by a dotted line 35 in Figure 4.

It may be noted, as best seen in Figures 1 and 4, that the tension member 4 at its outboard end is received within a complementary slot 36 in the rear web of the compression member and is seated against the rear wall 18 of the box-section portion of the brake head, the outboard end of the tension member 4 being diagonally sheared with respect to its longitudinal center line to afford a relatively great weld area contacting the slotted portion of the rear brake head wall 18.

The front wall 16 of the brake head is of conventional arcuate form and is reinforced by top and bottom vertical webs 38, 38 merging respectively with the top and bottom brake head walls 12 and 14 which are slightly offset at 40 and 42 respectively adjacent their forward extremities which merge with the before-mentioned front wall 16. The front wall 16 is formed on the forward face thereof with end and intermediate brake shoe engaging lugs 44, 44 adapted for connection in conventional manner to associated brake shoe means (not shown).

Figures 5-8 inclusive illustrate a modification of the invention wherein the truss structure comprises a channel or U-section compression member 52, a tension member 54, and a strut 56 connected therebetween, said strut comprising a slot 58 for the reception of an associated brake lever (not shown).

Each end of the modified beam is provided with a brake head generally designated 60 comprising a box-section portion including top and bottom walls 62 and 64 offset adjacent their forward ends at 66 and 68 respectively to merge with an arcuate portion 70 of the front brake head wall 72, said arcuate portion 70 defining a hanger slot 74 adapted for the reception of an associated brake hanger (not shown). The box-section portion of the brake head also comprises a rear wall 76 slotted as at 78 to accommodate a weld as hereinafter described.

The top and bottom walls 62 and 64 are connected at the outer or outboard extremities thereof by an end wall 80 slotted as at 82 for the reception of the tension member 54, and the end wall 80 is provided on the outer surface thereof with a hollow projection or lug 84 receiving the outer end of the tension member 54 which is snugly fitted within a socket or slot 86 within the lug or boss projecting at 84 from the outboard brake head end wall 80. The compression member 52 is snugly fitted within the box-section portion of the brake head, the top and bottom webs of the compression member being in snug abutment with the top and bottom walls 62 and 64, as best seen in Figure 8, and the rear web 88 of said compression member being in abutment with the rear web 76 of the brake head.

It may be noted, as best seen in Figures 5 and 8, that the rear web 88 of the compression member is provided with a slot 90 extending inwardly from the outer extremity of the compression member and registering with the before-mentioned slot 78. A filler block, generally designated 92, is fitted within the compression member 52 in abutment with the top and bottom and rear webs thereof, said block affording back-up metal for a weld within the slots 78, 82 and 90. This weld, as in the previously described embodiment, fuses the outboard end of the tension member with the rear web 88 and the wall 76 of the compression member and brake head respectively and with the filler block 92 which is bifurcated as in the previously described em-

bodiment so as to snugly embrace the tension member 54 at the outboard end thereof to provide an exceptionally rigid beam.

It may be noted that the offset portions 66 and 68 of the top and bottom brake head walls 62 and 64 are integrally formed with an inner end wall 96 comprising a slot or socket 98 receiving the tension member 54 to afford guide means therefor, as in the previously described embodiment.

The front wall 72 of the brake head is provided on the forward face thereof with end and intermediate lugs 100, 100 adapted for connection in the conventional manner to associated brake shoe means (not shown).

Referring now to Figures 9 and 10, another modification of the invention is illustrated wherein the brake head generally designated 102 comprises a box-section portion including a rear wall 106, top and bottom walls 108 and 110, and inboard and outboard end walls 112 and 114. The beam also comprises a truss structure including tension and compression members 120 and 122 interconnected by a strut 124 with a diagonal lever slot 126.

The compression member 122 is a channel or U-section member snugly fitted within the box-section portion of the brake head with the rear web of said member bearing against the wall 106 and the top and bottom webs of said member bearing against the top and bottom walls 108 and 110 respectively.

The tension member extends through a diagonal socket or slot 128 (Figure 9) in the inboard end wall 112 of the brake head 102 and through a complementary opening 130 in the outboard end wall 114 which is provided with a hollow boss 132 on the outboard face thereof. The boss 132 comprises an internal socket or pocket 134 receiving the outboard end of the tension member 120, the outboard extremity of which is sheared as in the previously described embodiments of the invention.

It will be understood that the tension member 120 is welded to the brake head 102 within the socket 134 which is conveniently adapted to receive the weld metal.

As best seen in Figure 10, the top and bottom walls 108 and 110 are offset toward each other at their forward edges to merge with an arcuate portion 136 of the front or forward wall 138 of the brake head, said arcuate portion affording a hanger socket for the reception of conventional brake hanger means (not shown).

The front or forward wall 138 of the brake head is provided with lugs 140 adapted for connection in the conventional manner to associated brake shoe means (not shown); and said wall 138 is reinforced by top and bottom vertical ribs 142, 142 as in the previously described embodiments of the invention.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a fabricated truss type brake beam, a brake head with a hollow portion including a rear wall, top and bottom walls connected thereto, and an outboard wall connected to said rear wall and to said top and bottom walls, an opening through said outboard wall, a hollow boss formed on the

outboard face of said outboard wall and comprising an internal socket communicating with said opening, a U-section compression member fitted within said portion in abutment with all of said walls, a tension member extending into said compression member and outboardly through said opening into said socket, and a weld in said socket connecting said tension member to said boss.

2. In a fabricated truss type brake beam, a brake head with a hollow portion including an outboard end wall with an opening therethrough and a boss on the outboard face thereof, a socket within said boss communicating with said opening, a U-section compression member received within said portion, a tension member received within said compression member and extending through said opening into said socket, and a weld in said socket connecting the outboard end of said tension member to said boss.

3. In a fabricated truss type railway brake beam, a brake head having a front brake shoe supporting portion, and a rear hollow portion comprising a rear wall and an outboard end wall with an opening therethrough, a boss on the outboard face of said end wall having a socket communicating with said opening, a U-section compression member received within said hollow portion and having a rear wall bearing against the rear wall of said hollow portion, a tension member received within the compression member, a slot in said compression member wall receiving a portion of the tension member, the outboard end of said tension member extending through said opening into said socket, and a weld connecting said rear walls to said tension member, said weld extending into said socket to connect the outboard end of the tension member to said boss.

4. In a fabricated truss type railway brake beam, a brake head having a front brake shoe supporting portion, and a rear hollow portion comprising a rear wall and an outboard end wall with an opening therethrough, a boss on the outboard face of said end wall having a socket communicating with said opening, a U-section compression member in telescopic relationship with said hollow portion, said compression member having a rear wall bearing against the rear wall of said hollow portion, a tension member received within said hollow portion and said compression member and extending through said opening into said socket, a weld in said socket connecting the outboard end of the tension member to said boss, a bifurcated filler block seated on the tension member, said block having a surface seated against one of the rear walls and having spaced legs seated against the top and bottom of the tension member and having a surface diagonal to said rear walls seated against the tension member and joining the first-mentioned surface, said block being secured by said weld to the tension member and to said one rear wall.

5. A truss type brake beam comprising a U-section compression member having top and bottom walls and an upstanding web extending therebetween, a brake head having a front brake shoe supporting portion and having a rear hollow portion including an upstanding web bearing against the first-mentioned web along complementary surfaces, a tension member housed within the compression member and said hollow portion and having a rear surface positioned adjacent one of said webs, a bifurcated filler block having a surface diagonal to said webs and bearing against said tension member from approximately the top to the bottom thereof, said block having spaced

legs with opposed top and bottom surfaces seated against the top and bottom respectively of said tension member and joining the diagonal surface, said block and legs having flat coplanar surfaces bearing against said one web and joining said diagonal surface and said top and bottom surfaces to afford a dam preventing flow of molten weld metal between the tension member and said one web, and a weld joining the block, the tension member rear surfaces, and said one web in an integral structure.

6. In a fabricated truss type railway brake beam, a brake head having a front brake shoe supporting portion, and a rear hollow portion comprising a rear wall and an outboard end wall with an opening therethrough, a boss on the outboard face of said end wall having a socket communicating with said opening, a U-section compression member having a rear wall bearing against the rear wall of the brake head portion, a tension member received within the compression member and extending through said opening into said socket, a bifurcated filler block embracing the tension member and seated against one of said rear walls along the top and bottom margins of the tension member and extending outboardly to said opening, said block comprising surfaces diagonal to said rear walls and seated against the tension member, and a weld connecting said tension member to said one rear wall, said weld extending into said socket to connect the tension member to said boss, the block being formed and arranged to afford a dam preventing flow of molten weld metal along the tension member and said one rear wall and being fused to said one rear wall and to the tension member by said web to reinforce the connection therebetween.

7. A truss brake beam, including a compression member, a tension member bent in the middle and having divergent halves away from the bend, and each half extending substantially at the same slant as the other and continuously at one slant for the full length thereof to its terminal, and the terminals crossing the ends of the compression member at such slant and extending beyond the compression member, and truss locks around the crossings of the members and having beam guiding extensions receiving the thus continuously slanted extended ends of the tension member.

8. A truss brake beam, including separate compression and tension members, truss locks fixing the ends of the members together and having longitudinal extensions constituting means for guiding the beam on side members of a car truck, the truss locks having openings adjoining the ends of the compression and tension members, and the compression member having openings registered with the aforesaid openings, the ends of the tension member extending into the truss lock extensions, and the openings in the truss locks being in the shape of longitudinal slots extending into the extensions of the locks, where their outer ends are opposite the extended ends of the tension member, and the openings in the compression member registered with the inner ends of the slots, and through the slots and compression member openings uniting the truss locks, the extensions thereof and such members by welding.

9. A truss brake beam, including a tension member and a compression member longitudinal surfaces of the two members in mutual contact at both ends of the beam, means connecting the members thereat, and truss locks maintaining

the connections and provided with sockets having transverse outer end walls and receiving the ends of both members, the compression member abutting the outer end walls of the sockets, and the end walls having openings into which extend the ends of the tension member.

10. A truss brake beam according to claim 9, wherein the truss locks are provided with relatively reduced longitudinal channels forward of the sockets and receiving forward edge portions of the ends of the tension member.

11. A truss brake beam, including tension and compression members, the ends of the tension member being substantially flat in the horizontal plane of the beam and the compression member 15 of channel form, and the rear edges of the ends of the tension member contacting the web of the compression member along between the flanges thereof and spaced away from the flanges, means for attaching the ends of the two members, and truss locks having sockets receiving the attached ends of the two members, the outer ends of the sockets provided with horizontally slotted walls, and the thus spaced ends of the tension member extending into the slots.

12. A truss brake beam according to claim 11, wherein the truss locks are provided in front of the sockets with channels forming forward reductions thereof and in which fit the front edges of the ends of the tension member.

13. A lock for the truss of a brake beam, comprising a block-like body having a socket with an outer end wall and extending from its inner end to the wall at its outer end and the socket located at the back portion of the body, a front wall, and an intermediate, reduced, neck-like portion between the upper and lower surfaces of the body and extending longitudinally of the body between the front wall and the socket, the outer end wall having a transverse slot opening into the socket.

14. A truss brake beam including compression and tension members connected together at their ends, housings around the connected ends of the members, and in each housing a pair of mutually facing spaced walls between and by which the ends of the tension member are engaged, said walls terminating in rearwardly facing surfaces defining sockets with interior forwardly facing and interior upper and lower surfaces of the 50 housings, said sockets receiving the ends of the compression member.

15. A truss brake beam including compression and tension members connected together at their ends, truss locks around the connected ends of the members, each truss lock having interior walls with substantially horizontal surfaces spaced apart sufficiently to engage across the end of the tension member positioned between them, said walls terminating in rearwardly facing surfaces defining sockets with forwardly facing interior surfaces and with upwardly and downwardly facing interior surfaces of said locks, and the compression member engaged in said sockets, the middle horizontal plane of the locks extending 65 between said horizontal surfaces and said horizontal surfaces projected rearwardly from the front walls of the truss locks.

16. A truss lock having a rear socket adapted to receive the end of a channel compression member of a truss brake beam, the lock having interior spaced apart walls projected rearwardly from the front wall of the lock, said walls having mutually facing surfaces extending rearwardly from said front wall at approximately the mid-height thereof, said lock having rearwardly facing surfaces terminating the spaced walls, said rearwardly facing surfaces in conjunction with interior forwardly facing and interior upper and lower surfaces of the lock defining the socket, and said mutually facing surfaces adapted to engage between them the end of a tension member of such a brake beam.

17. A truss lock, according to claim 16, wherein in the back wall of the lock is provided with means adapted for assuring the rigid securement of the lock to such a compression member.

18. A truss lock, according to claim 16, wherein in the back wall of the lock is provided with a longitudinal slot adapted for the rigid securement of the lock to such a compression member by welding.

19. A truss lock, according to claim 16, wherein in the lock has a hollow longitudinal extension adapted to guide the end of such a beam and is provided with a slot which runs along the extension.

20. A truss lock, according to claim 16, wherein in the spaced apart walls are connected with the upper and lower walls of the lock to afford reinforcement therefor.

21. A truss lock in the form of a housing adapted for receiving an end of a truss of a brake beam, said lock comprising a socket, the wall of which is continuous to completely surround such end, and a slot in the back of the lock communicating with the socket, the slot adapted to receive a weld, and the lock provided with a hollow end extension adapted for guiding a brake beam, and the slot in the lock running along such extension.

22. A truss brake beam including tension and compression members, the tension member having divergent ends extending outwardly therefrom in substantial alignment, truss locks provided with sockets receiving the ends of the two members, the outer ends of the sockets having walls provided with openings and the terminals of the compression member abutting the walls, the tension member having engagement with the locks inwardly and outwardly of said walls.
